US0D1076791S

(12) **United States Design Patent** (10) **Patent No.:** **US D1,076,791 S**
Zhang (45) **Date of Patent:** **** May 27, 2025**

(54) **RECHARGEABLE BATTERY**

(71) Applicant: **Dongjie Zhang**, Cangzhou (CN)
(72) Inventor: **Dongjie Zhang**, Cangzhou (CN)
(**) Term: **15 Years**
(21) Appl. No.: **29/907,486**
(22) Filed: **Jan. 7, 2024**
(51) LOC (15) Cl. **13-02**
(52) U.S. Cl.
USPC **D13/103**
(58) **Field of Classification Search**

CLAIM

The ornamental design for a rechargeable battery as shown and described.

DESCRIPTION

FIG. 1 is a front, left and top perspective view of a rechargeable battery showing my new design;
FIG. 2 is a rear, right and top perspective view thereof;
FIG. 3 is a front view thereof;
FIG. 4 is a rear view thereof;
FIG. 5 is a right view thereof;
FIG. 6 is a left view thereof;
FIG. 7 is a top view thereof;
FIG. 8 is a bottom view thereof; and,
FIG. 9 is an enlarged view of a portion labeled as 9 on FIG. 1.

The long dash-short dash broken lines depict enlargement boundaries that form no part of the claimed design. The evenly broken lines illustrate portions of the article that form no part of the claimed design.

1 Claim, 9 Drawing Sheets
